AUTOMATIC FUSE SETTING APPARATUS

Ralph R. Chappell, Richmond, Va., and Rutger B. Colt, Baltimore, Md., assignors to Bendix Aviation Corporation, New York, N. Y., a corporation of Delaware

Application May 5, 1943, Serial No. 485,780

20 Claims.

(Cl. 86—23)

This invention relates to apparatus for setting relatively rotatable members to predetermined angular positions, and more particularly to improved apparatus for automatically setting the time fuses of projectiles in accordance with data transmitted from a remote point.

A large portion of the projectiles now in use by the various military forces of the world are provided with a fuse causing the explosion of the missile at a predetermined point in its trajectory. Since the forces maintaining the shell in its trajectory are known with relatively great accuracy, one of the simplest methods of detonating the shell charge is to use a time fuse, which is a fuse detonating the explosive at a predetermined time after the discharge of the projectile from the gun barrel. As different conditions of operation necessitate different trajectories, the time fuse is made adjustable to accommodate the requirements of the various conditions. The time fuse is usually set by rotating a fuse ring relative to the body of the shell and is adjusted for various times by adjustment of the fuse ring to corresponding predetermined angular positions. In addition, the fuse design is such that for one position of the fuse ring, the detonator and the explosive are isolated from each other, and this position of the fuse ring is known as the "Safety" position. The fuse ring is maintained in the safety position at all times, until immediately before insertion of the shell in the breech of the gun in which it is to be employed.

In recent years, projectiles of the above type have found wide employment in anti-aircraft ammunition, and due to the rapid and evasive action of the target, necessitating continuous changing of the fuse settings of the projectiles to be employed, there has appeared an urgent need for a fuse setter which will quickly and accurately set the fuses of the projectiles employed in accordance with the director data. Manual setting and setting by manually operated machines have been found deficient in action against modern high-speed aircraft. Further, it has been found necessary to standardize the time elapsing between the receipt of the director data and the discharge of the shell, as unless this time is standardized no accurate prediction of the target position when the shell reaches the desired range can be made. Standardization of this time is inherently difficult in manually operated fuse setting apparatus because of the variable qualities of the human element. Also, upon the cessation of firing, an unfired shell thereof usually remains in the breech of the gun which

must be removed and the fuse thereof set to safety position. An automatic fuse setter should preferably have means for performing the safety reset operation.

5 One of the principal objects of the invention is to provide a new and novel fuse setter for setting projectile fuses in accordance with remotely derived and transmitted data.

A further object of the invention is to provide 10 automatic fuse setting apparatus with a standardized setting time.

Another object of the invention is to provide 15 automatic fuse setting apparatus with a load operated switch for controlling the setting operation.

Yet another object of the invention is to provide 20 automatic fuse setting apparatus in which the setting operation is controlled by the relative angular position of the setting members independently of the absolute angular position thereof.

Still another object of the invention is to provide 25 automatic fuse setting apparatus in which the fuse ring is completely disengaged from the driving mechanism upon the completion of the setting operation.

A still further object of the invention is to provide 30 automatic fuse setting apparatus with means for setting the fuses to safety position independently of the director data supplied thereto.

The above objects and advantages of the invention are accomplished by providing relatively 35 movable reference and set rings with means for engaging the body and fuse ring of a projectile respectively, means for disengaging said set ring from said fuse ring when said reference ring and said set ring are in a predetermined angular position, means for preventing said disengagement in the absence of load on said reference and said 40 set rings, and means for preventing said disengagement until said reference ring and said set ring have revolved relatively through a predetermined minimum angle.

Other objects and advantages of the invention 45 will in part be disclosed and in part be obvious when the following specification is read in conjunction with the drawings in which:

Figure 1 is an exploded isometric view showing the details of the mechanism.

50 Figure 2 is a detail view of the load operated pawl switch.

Figure 3 is a schematic diagram showing the connections of the electrical circuits and elements employed in conjunction with the apparatus.

55

Figure 4 is a sectional view of a completed fuse setter constructed in accordance with the teachings of the invention.

Figure 5 is a drawing showing in detail a portion of the mechanism for disengaging the driving connection between the set ring and the projectile fuse ring.

In the drawings like parts are designated by like reference characters.

Referring now to Figure 1, there is shown the motor 1 provided with pinion 2 driving the planetary case 3. The planetary pinions 4 and 5 rotate on shafts supported by the upper and lower members of the case 3. Pinions 4 and 5 are of different diameters and mesh respectively with the set sun ring 6 and with the reference sun ring 7. The reference sun ring 7 is provided with a resiliently mounted pawl 8 and a second resiliently mounted pawl 9 is carried by the set ring 6. Pawl 8 is termed the reference pawl and pawl 9, the set pawl.

Pawl 9 controls the switch 10 shown in greater detail in Figure 2. The pawl 9 is pivotally mounted on the pawl carrier 11 supported from the set ring 6 by the spring 12. A movable switch contact 10a is carried by an extension of the pawl 9 and upon counterclockwise rotation of the pawl 9 about its pivotal mounting, moves into engagement with the adjacently located fixed switch contact 10b. The set ring 6 normally rotates counterclockwise and so long as pawl 9 is unloaded, the switch 10 is in the open position. Upon the pick-up of load by pawl 9, this portion of the assembly rotates about the pivot, closing the switch 10. The cooperation of this load operated pawl switch with the remainder of the apparatus will be later described.

The set take-off gear 13 is affixed to the set ring 6 by the screws 14 and rotates therewith. The gear 13 is provided with insulated annular conducting members 15 electrically connected with the switch contacts 10a and 10b of the pawl switch 10 and engaged by the cooperating brushes 16 through which the electrical energy is transferred to the remainder of the apparatus. The gear 13 engages the planetary drive gear 16 provided with a hub 17 on which is wound the spring 18. One end of the spring 18 is secured to the fuse setter casing by the screw 19. The action of the spring 18 on the brake drum 17 permits clockwise rotation of the gear 16 but resists the counterclockwise rotation thereof. The gear 16 is connected by the shaft 20 with the differential planetary 21, and another shaft 22 from the planetary 21 is connected to the reference ring 7 through the planetary drive gear 23, idler gear 24, and take-off gear 25 which is secured to the reference ring 7 by screws. The ratio between gears 13 and 16 and gears 23 and 25 respectively is such that if either the set or the reference ring be held while the other is rotated a full revolution, this movement will cause a complete revolution of the casing of planetary 21 which has the conventional spur gear internal construction. As a result, the absolute angular position of the planetary 21 corresponds to the relative angular position of the set ring 6 and the reference ring 7 independently of their absolute angular positions.

The pawl 9 is provided with a sloping face, and directly above is located a hold-out member 26 or, as it may also be called, a knock-out member, normally engaging this face and displacing the pawl 9 radially outwards. The member 26 is linked to the plunger 27 by the latching pawl 28 75

hinged to the lever 29. Upon the insertion of a projectile 30 with the reference notch 31 and the set notch 32, the nose 33 thereof engages plunger 27 forcing it upward, thereby lifting the member 26 from its normal position and permitting the pawl 9 to move radially inward under the influence of the spring 12. At the same time, the rod 34 on member 26 engages the bell crank 35 causing it to actuate switch 36 which energizes the motor 1 through suitable relay circuits to be later described. The motor 1 then drives the planetary case 3 clockwise which, due to the action of the spring brake 17, 18 and the relative sizes of pinions 4 and 5, drives the reference ring 7 in a clockwise direction. The reference ring 7 continues its rotations until the pick-up of load by pawl 8 through the engagement of the notch 31, whereupon ring 7 becomes stationary and set ring 6 begins counterclockwise rotation. As the pawl 9 engages the slot 32 in the fuse ring, the additional load closes switch 10 in the manner above outlined. The fuse ring 32 is then continuously rotated with respect to the projectile 30 until the motor 1 is stopped or pawl 9 disengages the slot 32.

In the normal sequence of operations, pawl 9 is disengaged from slot 32 by the return of the hold-out member 26 to its normal position. The rod 34 mounted on member 26 is surrounded by a restoring spring 37 having the lower end fixed to the case of the apparatus and the upper end provided with a cap which is displaced by the rod 34. The displacement of member 26 by insertion of the projectile 30 puts spring 37 under tension but the member 26 is constrained to follow the movements of the push rod 27 by the action of the latching pawl 28. This pawl is normally held in engagement with a flange at the top of member 26 by the spring 38 and has an end attached to a control link 39 operated by a solenoid 40. Excitation of the solenoid 40 moves the control link 39 to the right, disengaging the pawl 28 from the hold-out member 26 which then snaps back to the normal position under the action of spring 34, knocking the pawl 9 out of engagement with the slot 32. The apparatus controlling solenoid 40 is discussed at greater length in a following paragraph.

The director data is received from a remote point by a self-synchronous electric motor 41 which rotates the shaft 42 with the attached gear 43 and contact member 44 in accordance therewith. The gear 43 drives the gear 45 connected to the jack shaft 46 which rotates the dial 47 to indicate the directed fuse settings by the action of dial pointer 48 moving over the adjacently disposed scale 49. The contact member 44 is located within a rotatable cup shaped assembly 51 having an arm 50 projecting inwardly and making contact with the member 44 as it sweeps by the end of the arm 50. The assembly 51 is constructed of insulating material and provided with slip rings 52 and 53 on the exterior thereof. The arm 50 is electrically connected to slip ring 52 and a brush 54 extending radially inward from the periphery of the cup is electrically connected to slip ring 53 and makes contact with the end of shaft 42 which is electrically connected with the member 44. The entire assembly just described may be referred to as a cup-switch and the electrical connections between this switch and the rest of the apparatus are established through the brushes 55 riding on the slip rings 52 and 53. The cup-switch is mounted on a suitably journaled second shaft 56 which is driven

by the gear 57 engaging the periphery of the planetary differential 21. An electrical circuit is thus completed between the brushes 55 whenever the position of the casing of the planetary differential 21 corresponds to the angular position of the shaft 42 which is driven in accordance with the director data by the motor 41, which is to say, that this circuit is completed whenever the angular position of the set ring 6 with respect to the reference ring 7 corresponds to the setting derived from the director. 10

The pin 58 is mounted near the periphery of the gear 57 and momentarily closes the adjacently disposed switches 59 and 60 during its passage thereby. Switch 59 is so positioned that it is actuated whenever the relative position of it is actuated whenever the relative position of the set ring 6 and the reference ring 7 corresponds to the "Safe" fuse setting, and switch 60 is actuated when this relative position corresponds to the 7-second fuse setting. The actual position of switch 60 is relatively unimportant so long as the switches are separated by a sufficient angle to prevent overlapping operation and the 7-second angular position was chosen in the particular application since it afforded a convenient standard value with the projectile concerned. 15

The operation of the apparatus is most readily understood by consideration of the previous figures in connection with the schematic diagram of Figure 3 showing the motor 1 having a lead 62 connected directly to the 3-phase line 61 and the leads 63 and 64 connected to the remaining two conductors of the line 61 through two contacts of the motor control relay 65. The winding of relay 65 is connected across a single phase in series with the switch 36 which is controlled by the bell crank 35. The contacts of relay 65 are normally in the open position and are moved to the closed position when the operating winding is energized. A third set of contacts on relay 65 is connected to a single phase of line 61 through the normally closed contacts 69 of the latch release solenoid 40 and the operating winding of the light relay 66. Relay 66 is provided with two sets of contacts, one set of said contacts controlling the connection of indicating lamps 67 and 68 to a source of electrical energy (not shown). When relay 66 is in the normal or unoperated condition, the green lamp 68 is illuminated and when in the operated position, the red lamp 67 is energized. The second set of contacts on relay 66 is connected to the operating winding of the relay 66 and to the line 61 through the contacts of the solenoid switch 69. This insures that, without regard to the position of the motor control relay 65, once the red light has been illuminated, energy cannot be reapplied to the green light until the operation of solenoid 40 has released the knock-out member 26, disengaging the pawl 9. 20

The winding of solenoid 40 is connected in series with anode circuit of the cold-cathode discharge device 70 which may be of the type commercially designated 631P1 or Strobotron. The discharge device 70 is provided with a cathode 71, inner grid 72, outer grid 73, and anode 74. The energy for the control of solenoid 40 is derived from the transformer 75 having a primary winding 76 connected to the line 61, with a center tapped high voltage 77 connected to the anodes of the discharge device 78, whose cathode is energized from the secondary winding 79. A commercial vacuum tube rectifier known com- 25

mercially as the type 524 has been successfully employed as discharge device 78. The center tap of winding 77 is connected to ground through resistor 80 which may have a value of 1 megohm. A filter condenser 81 is connected between the cathode of tube 78 and the center tap winding 77 in parallel with the adjustable potentiometer 82. When used with 60 cycle energy a value of 10 microfarads has been found satisfactory for capacitor 81 together with a value of 100,000 ohms for potentiometer 82. The capacitor 83 is also connected across the output of rectifier 78 in series with the resistor 82. The values of capacitor 83 and resistor 84 vary with the characteristics of the solenoid and discharge devices employed, and in a particular structure a value of 60 microfarads has been found satisfactory for capacitor 83 in conjunction with a value of 9000 ohms for the resistor 84. 30

The cathode 71 and inner grid 72 of discharge device 70 are connected to the negative terminal of capacitor 83, and the solenoid 40 is connected between the anode 74 and the positive terminal of capacitor 83. The outer grid 73 is connected to cathode 71 through resistor 85 having a value of 1 megohm and is also connected to the control capacitor 86 through resistor 87 and the paralleled switches 88 and 89. Switch 88 is a manually operable momentary contact switch not previously mentioned, and switch 89 represents the cup-switch previously described. The remaining terminal of control capacitor 86 is connected to cathode 71. 35

The movable arm 89 of potentiometer 82 is connected to the positive terminal of capacitor 86 through the load responsive pawl switch 10, the momentary "Safe" switch 59, and one set of contacts of the delay relay 91. The "Safe" switch 59 is one of the previously mentioned switches operated by the pin 58 on the gear 57. The operating winding of the delay relay 91 is connected in parallel with the operating winding of light relay 66 in series with the 7-second switch 60, which also is one of the switches operated by the pin 58 on the gear 57. Upon the movement of the contacts of relay 91 to the operated position, the lower contacts short circuit switch 60 and maintain the relay 91 in the operated position until the operation of solenoid switch 69 to interrupt the holding current. It is seen from inspection that capacitor 86 can be charged by the closure of "Safe" switch 59 only if the 7-second switch 60 has previously operated to operate relay 91. Thus, until relay 91 is in the operated position, no charge can be placed on capacitor 86. The operation of the apparatus is as follows: 40

The insertion of the projectile 30 in the apparatus displaces push rod 27 and bell crank 35, closing switch 36 which energizes motor control relay 65, starting the operation of motor 1. Operation of relay 65 closes the operating circuit of light relay 66, energizing the red light and closing a holding circuit on relay 66. The red light indicates that the fuse timing operation has not yet been completed. The motor 1 now drives the planetary case 3 and reference ring 7 clockwise until the pawl 8 engages the notch 31 in the shell body, at which time the reference ring 7 ceases to rotate because of the additional imposed load, and reference ring 6 begins to rotate in a counterclockwise direction. As the pawl 9 engages the notch 32 and picks up the load of the fuse timing ring, the switch 10 is closed. In general, the 7-second switch 60 will not have previously 45

70 75

operated so that the subsequent passage of the fuse timing ring through the "Safe" position, closing switch 59, does not charge capacitor 86. The timing ring continues to rotate and passes through the 7-second fuse setting position, at which time, switch 60 closes, operating relay 91 to connect the switches 10 and 59 to capacitor 86. As the fuse ring now passes through the "Safe" position, switch 10 is closed because of the load on the pawl 9, and the switch 59 is closed momentarily by the pin 58 to charge capacitor 86 in accordance with the setting of the potentiometer arm 90. Upon the continuing rotation of the set ring, the cup-switch 89 is driven by the shaft 56 and ultimately, the arm 50 engages the contact member 44, connecting capacitor 86 to the outer grid 73 of the discharge device 70. This initiates a discharge through the tube 70, and the surge anode current from the capacitor 86 through the solenoid 40 displaces the control link 39 to move the latching pawl 28 and release the knock-out member 26 which snaps back to normal position to disengage the pawl 9 from the fuse timing ring notch 32. The final setting of the fuse ring is therefore determined by the relative positions of the shafts 42 and 56 from the self-synchronous motor 41 and the gear 57 driven by the differential 21. The motor 1 is de-energized simultaneously with the disengagement of pawl 9, but its inertia characteristics have no effect on the fuse setting since the fuse setting member is completely disengaged from the fuse timing ring. If desired, the motor 1 may be permitted to operate continuously. The energizing of solenoid 40 also momentarily operates switch 69 removing power from relays 66 and 91 to restore them to the normal position with their holding circuits open. The green light 69 is now illuminated, indicating that the projectile may be withdrawn from the fuse setter and the next one inserted.

The inclusion of the load operated switch 10 insures that, should the pawl 9 fail to engage the fuse ring, no green signal will be given and the operator is informed of the fact that the setting operation has not been completed. If the 7-second switch 60 with the delay relay 91 is omitted, the setting operation on many projectiles is completed within a few tenths of a second as the projectiles are stored with the fuse in a "Safe" position, and load switch 10 and "Safe" switch 59 close simultaneously. Projectiles having fuse setting other than safety, however, require up to 1½ seconds for the completion of the setting operation, as first the pawl switch 10 operates in response to the load pick-up and later the switch 59 operates upon passage through the "Safe" position. This provides a wide possible range of setting times with consequent inaccuracies in shooting. The combination of switch 60 with its associated relay 91 and the switch 59 insures very nearly a full revolution at all times, thereby reducing the factor of variation in setting time from 10:1 to 1.5:1.

When it is desired to set a projectile fuse to "Safe," the projectile is inserted in the fuse setter and the manual set safe switch 88 operated by the attendant.

In this condition of operation the fuse setting 70 is independent of the cup-switch 89, as the solenoid 40 is operated immediately upon the closure of the safe switch 59. Although the switch 60 has been referred to as the 7-second switch, it is to be understood that any other fuse timing 75

providing sufficient angular separation between the "Safe" and delay switches is satisfactory.

Although the exploded isometric view of Figure 1 makes the operational principles of the apparatus clear, many of the practical details of the construction of a fuse setter have been omitted for the purpose of clarity. The sectional view of Figure 4 shows all the aforementioned parts in the positions which they assume in a practical embodiment of the invention. The instrument includes a case 92 with a removable backing plate 93 and housing 94 secured in place by the screws 95. The forward end of the case 92 is closed by the frontal plate 96 on which is mounted the shell guide 97. Adjacent the shell guide is one of the indicating lamps 68 behind the colored jewel 98, and the guide 97 is provided with apertures 99 for the transmission of illumination from the lamp 68 to the opening of the guide for convenience in night operations. The self-synchronous motor 41 is secured to the backing plate 93 and the gear 43 on the shaft of motor 41 meshing gear 45 drives the indicating dial 47 through the shaft 46. The cup-switch 89 is located coaxially with the shaft of motor 41 and bears the two slip rings 52 and 53 on the exterior thereof which are engaged by the contact brushes 55. On the brush carrier 100, there is located the lower half 101 of a separable connector whose upper half 102 disengages therefrom on the removal of backing plate 93 to which it is attached. The contact member 44 driven by the motor 41 is not visible in this view.

A cooperating scale 49 is affixed to the frontal plate 96 adjacent the dial 47 and illuminated by the lamp 103 with the aid of the light conducting "Lucite" ring 104. Bosses on the plate 96 provide a mounting for the bezel 105 carrying a transparent dial glass 106 and the light baffle 107 which prevents the observer from directly viewing the source of illumination.

Also carried on the back plate 93 is the lever 29 swiveled on a boss forming a part of the plate. The end of lever 29 is engaged by the push rod 27 which is here shown displaced by the nose 33 of the projectile 30. The latching pawl 28 is hinged to the lever 29, and the spring 38 provides the force necessary to maintain the pawl 28 in engagement with the knock-out member 26. The lower end of pawl 28 is connected by a pin to the control link 39 of the solenoid 40. The nose of the projectile is received in a ball-bearing nose guide 108 mounted in the bearing cup 109 forced into the backing plate 93. As earlier described the upper movement of the push rod 27 displaces the bell crank 35 to actuate the switch 36, these parts also being mounted on the backing plate. The knock-out member 26 is here shown in the elevated position which permits the pawl 9 to engage fuse ring notch 32 and close the pawl switch 10. The knock-out member 26 is slideable on the exterior of the bearing cup 109.

The planetary casing 3 is driven clockwise by the motor 1 (not shown in this view) and the pinions 4 and 5 journaled in the upper and lower members thereof are clearly visible. The pawl 8 of the reference sun ring 7 is here shown in engagement with the notch 31. The set ring take-off gear 13 is provided with an insulating layer 110 on which are mounted the slip rings 15. One of the brushes 55 which engage the slip rings as is visible in Figure 1. The take-off gear 13 meshes the planetary drive gear 16 having the brake-drum 17 and the brake spring 18. The

shaft driven by gear 16 in turn drives the upper sun pinion of the planetary 21, and the lower sun pinion of planetary 21 is driven by the reference take-off gear 25 through an idler (not shown), engaging the planetary drive gear 23. As shown on the previous diagram, teeth on the exterior of the planetary housing 21 drive the gear 57 which actuates the cup 51 which is a part of the cup-switch 89. Each of the elements in this view operates in accordance with the previous description, and it is shown here to illustrate the compactness of structure which may be achieved despite the many functions performed by the apparatus.

The mounting of the spring 37 for restoring the knock-out member 26 to normal position is shown in somewhat greater detail in Figure 5. The spring is threaded to a boss 111 on the backing plate 93 at its lower end and is closed by the cap 112 at the upper end. Displacement of the member 26 on the bearing cup 109 stretches the spring 37 by the action of the rod 34, and the displacement of the latching pawl 28 permits the rapid return of the member 26 to the normal position under the action of spring 37.

In considering the characteristics of this apparatus, it is important to note that the planetary assembly 21 always rotates in the same direction because of the action of the unidirectional brake and that the accuracy of the positioning is therefore substantially unaffected by the employment of fairly large tolerances on the gears. Although a differential mechanism has been shown for imparting relative motion to the set and reference rings, it is to be understood that any other method of producing the desired motion may be employed.

It will be obvious that many changes and modifications may be made in the invention without departing from the spirit thereof as expressed in the foregoing description and in the appended claims.

We claim:

1. In apparatus for setting relatively rotatable members to a predetermined angular position, a rotatable reference ring, means carried by said reference ring for engaging one of said members, a rotatable set ring, a resiliently mounted pawl carried by said set ring, motor means relatively driving said reference ring and said set ring, holdout means normally maintaining said set pawl in disengaged position, means displaceable upon the insertion of a body bearing said members, latching means connecting said holdout means and said displaceable means, electromagnetic means for operating said latching means, differential means responsive to the relative angular position of said reference ring and said set ring, means responsive to data transmitted from a remote point, a momentary electric switch jointly responsive to said differential means and to said data responsive means connected to said electromagnetic means, a manually operable switch connected in parallel with said momentary switch, a load operated switch controlling the response of said electromagnetic means to said paralleled switches, and a pair of switching means sequentially responsive to the relative rotation of said reference ring and said set ring for controlling the response of said electromagnetic means to said electrical switching means.

2. In apparatus for setting relatively rotatable members to a predetermined angular position, a rotatable reference ring, means carried by said reference ring for engaging one of said members,

5 a rotatable set ring, a resiliently mounted pawl carried by said set ring, motor means relatively driving said reference ring and said set ring, holdout means normally maintaining said set pawl in disengaged position, means displaceable upon the insertion of a body bearing said members, latching means connecting said holdout means and said displaceable means, electromagnetic means for operating said latching means, differential means responsive to the relative angular position of said reference ring and said set ring, means responsive to data transmitted from a remote point, a momentary electric switch jointly responsive to said differential means and to said data responsive means connected to said electromagnetic means, a manually operable switch connected in parallel with said momentary switch, a load operated switch controlling the response of said electromagnetic means to said paralleled switches.

25 3. In apparatus for setting relatively rotatable members to a predetermined angular position, a reference member, means carried by said reference member for engaging one of said rotatable members, a rotatable set ring, means carried by said set ring for engaging the other of said rotatable members, motor means driving said set ring, means responsive to the relative angular position of said reference member and said set ring for disengaging said means carried by said set ring from said rotatable member, and means for preventing said disengagement for predetermined values of relative rotation between said reference member and said set ring.

40 4. In apparatus for setting relatively rotatable members to a predetermined angular position, a rotatable reference ring, means carried by said reference ring for engaging one of said members, a rotatable set ring, means carried by said set ring for engaging the other of said members, motor means for relatively driving said reference ring and said set ring, means responsive to the relative angular position of said reference ring and said set ring for disengaging said means carried by said set ring from said member, and means for preventing said disengagement for predetermined values of relative rotation between said reference ring and said set ring.

45 5. In apparatus for setting relatively rotatable members to a predetermined angular position, a rotatable reference ring, means carried by said reference ring for engaging one of said members, a rotatable set ring, a displaceably mounted pawl carried by said set ring for engaging the other of said members, motor means relatively driving said reference ring and said set ring, holdout means normally maintaining said set pawl in disengaged position, means displaceable upon the insertion of a body bearing said members, latching means connecting said holdout means and said displaceable means, electromagnetic means for operating said latching means, differential means responsive to the relative angular position of said reference ring and said set ring, means responsive to data transmitted from a remote point, electrical switching means jointly responsive to said differential means and to said data responsive means connected to said electromagnetic means, a load operated switch controlling the response of said electromagnetic means to said electrical switch-

ing means, and a pair of switches sequentially responsive to the relative rotation of said reference ring and said set ring for controlling the response of said electromagnetic means to said electrical switching means, one of said last mentioned switches being connected in series with said load operated switch and the other of said last mentioned switches controlling means for connecting said load operated switch, said first mentioned electrical switching means and said first mentioned sequentially operated switch in series.

6. In apparatus for setting relatively rotatable members to a predetermined angular position, a rotatable reference ring, means carried by said reference ring for engaging one of said members, a rotatable set ring, a resiliently mounted pawl carried by said set ring, motor means relatively driving said reference ring and said set ring, holdout means normally maintaining said set pawl in disengaged position, means displaceable upon the insertion of a body bearing said members, latching means connecting said holdout means and said displaceable means, electromagnetic means for operating said latching means, differential means responsive to the relative angular position of said reference ring and said set ring, means responsive to data transmitted from a remote point, electrical switching means jointly responsive to said differential means and to said data responsive means connected to said electromagnetic means, a load operated switch controlling the response of said electromagnetic means to said electrical switching means, and a pair of switching means sequentially responsive to the relative rotation of said reference ring and said set ring for controlling the response of said electromagnetic means to said electrical switching means.

7. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means displaceable upon the insertion of a projectile, latching means connecting said holdout means and said displaceable means, electromagnetic means for operating said latching means, differential means responsive to the relative angular position of said reference ring and said set ring, means responsive to data transmitted from a remote point, electrical switching means jointly responsive to said differential means and to said data responsive means connected to said electromagnetic means, a load operated switch controlling the response of said electromagnetic means to said electrical switching means, and switching means responsive to the relative rotation of said reference ring and said set ring for controlling the response of said electromagnetic means to said electrical switching means.

8. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means operable upon the insertion of a projectile to displace said holdout means,

means responsive to the relative angular position of said reference ring and said set ring for restoring said holdout means to said normal position, load responsive interlock means for preventing said restoration for predetermined loads, and means responsive to the relative rotation of said reference ring and said set ring for preventing said restoration until said relative rotation exceeds a predetermined value.

9. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means operable upon the insertion of a projectile to displace said holdout means, means responsive to the relative angular position of said reference ring and said set ring for restoring said holdout means to said normal position, and means responsive to the relative rotation of said reference ring and said set ring for preventing said restoration until said relative rotation exceeds a predetermined value.

10. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means operable upon the insertion of a projectile to displace said holdout means, means responsive to the relative angular position of said reference ring and said set ring for restoring said holdout means to said normal position, and load responsive interlock means for preventing said restoration until said relative rotation exceeds a predetermined value.

11. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means displaceable upon the insertion of a projectile, latching means connecting said holdout means and said displaceable means, electromagnetic means for controlling said latching means, a load operated switch controlling said electromagnetic means, differential means responsive to the relative angular position of said reference ring and said set ring, means responsive to data transmitted from a remote point, and electrical switching means connected to said electromagnetic means jointly responsive to said differential means and to said data responsive means.

12. In apparatus for the setting of a projectile fuse time ring, a rotatable reference ring, means carried by said reference ring for engaging the body of a projectile, a rotatable set ring, a resiliently mounted pawl carried by said set ring, means for restraining the rotation of said set ring in a predetermined direction, motor means relatively driving said reference ring and said set ring, holdout means normally maintaining said pawl in disengaged position, means operable upon the insertion of a projectile to displace said holdout means and initiate the operation of said motor means, differential means responsive to the

relative angular position of said reference ring and said set ring, means responsive to data transmitted from a remote point, and means jointly responsive to said differential means and to said data responsive means for restoring said holdout means to said normal position and discontinuing the operation of said motor means.

13. In apparatus for the setting of a projectile fuse time ring, a rotatable reference ring, means carried by said reference ring for engaging the body of a projectile, a rotatable set ring, a resiliently mounted pawl carried by said set ring, means for restraining the rotation of said set ring in a predetermined direction, motor means relatively driving said reference ring and said set ring, holdout means normally maintaining said set pawl in disengaged position, means operable upon the insertion of a projectile to displace said holdout means, differential means responsive to the relative angular position of said reference ring and said set ring, means responsive to data transmitted from a remote point, and means jointly responsive to said differential means and to said data responsive means for restoring said holdout means to said normal position.

14. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and set ring, holdout means normally maintaining said set pawl in disengaged position, means displaceable upon the insertion of a projectile, latching means connecting said holdout means and said displaceable means, electromagnetic means for controlling said latching means, differential means responsive to the relative angular position of said reference ring and said set ring, means responsive to data transmitted from a remote point, and electrical switching means connected to said electromagnetic means jointly responsive to said differential means and to said data responsive means.

15. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means displaceable upon the insertion of a projectile latched to said holdout means, and means responsive to the relative angular position of said reference ring and said set ring for unlatching said holdout means and said displaceable means.

16. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally main-

taining said set pawl in disengaged position, means operable upon the insertion of a projectile to displace said holdout means, electromagnetic means for restoring said holdout means to said normal position, differential means responsive to the relative angular position of said reference ring and said set ring, means responsive to data transmitted from a remote point, and electrical switching means connected to said electromagnetic means jointly responsive to said differential means and to said data responsive means.

17. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means operable upon the insertion of a projectile to displace said holdout means, differential means responsive to the relative angular position of said reference ring and said set ring, means responsive to data transmitted from a remote point, and means jointly responsive to said differential means and to said data responsive means for restoring said holdout means to said normal position.

18. In apparatus for the setting of a projectile fuse time ring, a rotatable reference ring, means carried by said reference ring for engaging the body of a projectile, a rotatable set ring, a resiliently mounted pawl carried by said set ring, motor means relatively driving said reference ring and said set ring, holdout means normally maintaining said set pawl in disengaged position, means operable upon the insertion of a projectile to displace said holdout means, and means responsive to the relative angular position of said reference ring and said set ring for restoring said holdout means to said normal position.

19. In apparatus for the setting of a projectile fuse time ring, a rotatable reference ring, a pawl engaging the body of a projectile carried by said reference ring, a rotatable set ring, a pawl engaging said time ring carried by said set ring, motor means in driving connection with said reference ring and said set ring, and means responsive to the relative angular position of said reference ring and said set ring for disengaging said pawl carried by said set ring from said time ring.

20. In apparatus for the setting of a projectile fuse time ring, a rotatable reference ring, means carried by said reference ring for engaging the body of a projectile, a rotatable set ring, means carried by said set ring for engaging said time ring, motor means in driving connection with said reference ring and said set ring, and means responsive to the relative angular position of said reference ring and said set ring for disengaging said means carried by said set ring from said time ring.
